INVENTOR

John Mason,
BY Chas. C. Gill
ATTORNEY.

UNITED STATES PATENT OFFICE.

JOHN MASON, OF NEW YORK, N. Y.

TICKET-HOLDER.

SPECIFICATION forming part of Letters Patent No. 460,144, dated September 29, 1891.

Application filed May 13, 1891. Serial No. 392,567. (No model.)

To all whom it may concern:

Be it known that I, JOHN MASON, a citizen of the United States, and a resident of New York, in the county of New York and State 5 of New York, have invented certain new and useful Improvements in Ticket-Holders, of which the following is a specification.

The invention relates to improvements in ticket-holders; and it consists in a novel box 10 or receptacle, hereinafter described, to be carried in the pocket and adapted to hold a number of elevated-railroad, ferry, or analogous tickets in a manner rendering it convenient to detach them for use when desired.

15 The holder constituting the invention is particularly adapted for holding such tickets as are sold in long strips and folded back and forth one upon the other to form a rectangular package, the object being to afford an 20 adequate means for conveniently holding the package and leaving the upper or end ticket conveniently exposed for detachment.

The invention will be more fully understood from the detailed description hereinafter presented, reference being had to the accompanying drawings, in which—

Figure 1 is a top view, partly in section, of a holder constructed in accordance with the invention, the exposed ticket, which is the 30 full length of the box, being shown as turned outward at an angle, and hence has the appearance of being shortened. Fig. 2 is a central longitudinal section of same on the dotted line 2 2 of Fig. 1. Fig. 3 is a like section 35 of same, the tickets and slides being omitted. Fig. 4 is a central transverse section of same on the dotted line 4 4 of Fig. 2; and Fig. 5 is a detached perspective view of one of the slides, hereinafter referred to, which preserve 40 the package of tickets in compact form within the holder, while permitting the detachment of the upper end ticket.

In the drawings, A represents a box or receptacle adapted to receive the package B of 45 folded tickets and consisting of the bottom C and sides D D, the latter being provided with the longitudinal grooves E. Within the grooves E are arranged the slides F F', one being above the other and entering the sides

D D at opposite ends of the box. The slides 50 F F' will preferably be supplied with projecting handles or edges G for convenience in withdrawing them.

In the use of the holder the folded strip of tickets will be placed in the box A, as indicated in Fig. 2, after which the slides F F' will be placed in position, the slide F being inserted from one end of the box, between the second and third tickets at the top of the package, and the slide F' from the opposite end of 60 the box, between the first and second of said tickets, thus leaving the top ticket free and in position to be detached. After the top ticket has been removed the slide F' will be withdrawn and inserted in the first fold of the 65 package beneath the slide F, thus leaving another exposed ticket, and upon the removal of this ticket the slide F will be withdrawn and inserted in the first fold of the package beneath the slide F', whereby another ticket 70 will be left exposed. As the tickets are detached from the top of the package B the slides F' F are thus alternately worked downward in the folds of the package until all of the tickets have been removed. The grooves 75 E receive and direct the side edges of the slides F F' and bind said edges sufficiently to prevent the slides from working loose. In the removal of the tickets the inner end of the upper slide furnishes an edge against 80 which the tickets may be conveniently torn or detached. The slides effectually hold the folded strip of tickets in the box, and hence it is not necessary that the latter have closed ends.

85 In the drawings I have illustrated a strip or package containing ten tickets, with a box having nine grooves E for the slides; but I do not of course limit the invention to the carrying of any particular number of tickets 90 at one time, and hence the number of grooves E may be varied at will.

What I claim as my invention, and desire to secure by Letters Patent, is—

1. The ticket-holder consisting of the box 95 provided with the series of grooves, combined with the slides F F', substantially as and for the purposes set forth.

2. The ticket-holder consisting of the box having an open top and ends and provided in its facing sides with grooves, combined with the alternating slides entering said grooves, substantially as and for the purposes set forth.

3. The ticket-holder consisting of the box A, having the bottom C and sides D D and adapted to receive the folded strip of tickets forming a package B, combined with the alternating slides F F', entering between the

folds of said package, substantially as and for the purposes set forth.

Signed at New York, in the county of New York and State of New York, this 9th day of May, A. D. 1891.

JOHN MASON.
